Specification of Letters Patent.

Patented July 3, 1917.

Application filed June 7, 1916. Serial No. 102,353.

To all whom it may concern:

Be it known that I, SEVERIN HALVORSEN, citizen of the United States, and resident of Seattle, county of King, and State of Washington, have invented certain new and useful Improvements in Newspaper-Stuffing Machines, of which the following is a specification.

My invention relates to devices employed 10 to feed and assemble newspapers, pamphlets and like papers each of which consists of a series of folded sheets and consists more particularly of the mechanism employed in feeding the papers from a stack and delivering 15 them to the assembling mechanism.

The object of my invention is to produce a reliable, efficient and rapid mechanism for doing this work. The parts thereof which I claim as my invention will be hereinafter 20 described and then more particularly pointed out in the claims.

In the accompanying drawings I have shown, and hereinafter I will describe, the details of construction of the form of device 25 now most preferred by me for carrying out my invention.

Figure 1 is a side elevation of that part of an assembled machine which includes one set of paper feeding mechanisms.

30 Fig. 2 is a plan view of the same, the parts above the level of the paper supporting members being omitted.

Fig. 3 is an exterior elevation of the mechanism at the side from which the papers are 35 removed.

Fig. 4 is a side view of the main operative parts of the paper feeding mechanisms, the frame being sectioned on the line of the vertical paper feeding chains, the paper ejecting members being in retracted position.

Fig. 5 is a like view but with the paper ejecting members in extreme advanced position.

Fig. 6 is a section taken on line 6—6 of 45 Fig. 2.

Fig. 7 is a section taken on line 7—7 of Fig. 2.

Fig. 8 is a longitudinal section through the frictional feeding device used to actuate the feed mechanism which acts upon the 50 vertical edges of the pile of paper.

Fig. 9 is a section on the line 9—9 of Fig. 8.

Fig. 10 is an elevation of the front wall of

the paper storage chamber and the feeding 55 mechanisms associated therewith.

Fig. 11 is a section on the line 11—11 of Fig. 10.

Fig. 12 is a side view of a short section of the bar which carries the detent pawls 60 and which is shown in Fig. 10.

Fig. 13 is a face view of the same parts shown in Fig. 12.

Fig. 14 is a side view of one of the reciprocating paper feeding bars, the associated 65 frame guides being in section.

Fig. 15 is a plan view of like parts and Fig. 16 a section on line 16—16 of Fig. 15.

The subject of this invention consists of mechanism employed in connection with the 70 removal of a single paper at a time from a stack of papers, and as herein described and illustrated in the drawings, is intended for use in connection with a newspaper stuffing machine for the delivery of the papers to 75 the assembling and stuffing mechanism.

In such use the stack of papers is inclosed at two opposite sides, these conforming with the sides of the machine, by upwardly extending bars 1 and 10, of which the bars 1 80 at one side, are of considerable height, while the bars 10 are of slight length, the long bars 1 being placed at the side opposite that from which the papers are put in place and the short bars 10 at the side at which the attendant works.

These arms are provided with feet 11 by which they are bolted to the main frame. The long arm 1, may be fixedly bolted. It is often desirable that the width of the 90 hopper, or paper-receiving receptacle be adjustable in width, in which case one or the other set of the arms 1 and 10 may be adjusted, as is shown for the arms 10, in which the feet 11 have slots 12 for the clamping 95 bolts 13.

The forward wall of this paper receiving space is composed of a plate 2, which is slightly inclined from a perpendicular. This plate and the mechanisms associated therewith are separately shown in Figs. 10 and 11. This plate is provided with two sets of slots, the slots 20 for the reception of the detent dogs 15 and the slots 21 for the passage of the feed chains 3. The upper slot 21 105 of each pair may merge with a slot 20, as is herein shown.

The feed chains 3, each pass over gears 30,

31, carried respectively on shafts 32, 33, of which shaft 32 is the driver and 33 the driven. The chains pass from gears 30 through upper slots 21 to the face of the plate 2 which is next to the papers, thence down along the face of this plate to and through lower slots 21 to the gear 31. Idler and tightening gears 34 carried by arms 35 secured to rock shaft 36, engage the upward runs of chains 3. Arm 37 on shaft 36 carries an adjusting bolt 38, which engages with a fixed member, as the outer side of plate 2, to thereby adjust the tightening gears 34.

The shaft 32 is driven through a mechanism which is flexible, or compensating in the extent of its operation, whereby the movement of the chains 3 is ample for all occasions, but will be reduced in amount when encountering undue resistance. This has been secured by using a friction driving mechanism, as follows:

An arm 4, loosely mounted on shaft 32 is oscillated by means which will be later described. Secured to shaft 32 is a sleeve 40 having a flange 41. Sleeve 40 has a key way 45 into which fits teeth carried by disks 42 and 43 to compel rotation together. Spring 46 extending between disks 42 and 43 force them apart. A disk 44 screwed on sleeve 40, acts as an adjusting nut. Friction rings 47 are interposed between a ratchet wheel 49 and flange 41 on one side and disk 42 on the other. The ratchet wheel 49 is actuated a like amount at each reciprocation of arm 4, but the movement given shaft 32 will depend upon the slippage occurring between the rings 47 and their adjacent surfaces. If the resistance to movement of chains 3 is great, there may be little or no movement of the chains.

The arm 4 is oscillated by a link 53 from shaft 5 which is given an oscillating movement through crank arm 54, link 55 and crank pin 56 carried by main shaft 57. Shaft 5 has an arm 50, having a slot 51 for adjustment of pin 52, to which link 53 is connected.

The floor or bottom of the paper receiving chamber is inclined toward the forward side and the plate 2. The greater part of the front or lower part of the floor is supported from bracket arms 6, projecting from a cross bar or plate 60 of the frame. Between each pair of bracket arms 6, is placed a guide way member 61, which is shown in cross section in Fig. 16. This is of U-shape in cross section, to form a guide way for the reception of the reciprocating bars 7 which carry the paper feeding dogs 8 and 87.

The side walls of guideway 61 have grooves 62 in which fit ribs or wings 70 of the needle-carrying, paper-feeding bars 7. They are also recessed upon their upper edges to form cam guideways 86 extending beneath the flanges 63 and receiving cam

rollers 75 carried by the back-feeding dogs 87. Bars 7 are pivoted at 79 to links 88 which are connected to arms 58 carried by oscillating shaft 5, and are thus reciprocated. This connection with arm 58 is by a slot in arm 58, so that they may be readily disconnected.

The feed dogs 8 are pivoted on pins 74 and lie in recesses 71 formed in the side of bar 7. They each have an arm 80 which is bored to receive a needle 81 which is adjustable in projection by screw 83 and clamped by screw 82. A spring 84 acts to approximately compensate for the rotative effect of gravity on the dog.

The central portion 85 of the dog projects slightly above the upper face of the plates 63, that is, above the surfaces which support the papers. In consequence this part of the dogs has a considerable frictional engagement with the papers when they are reciprocated beneath them. This results in rocking the dogs immediately any relative movement occurs between them and the papers. For a backward movement of the bars 7, this will throw the needles down, out of paper-engaging position, while forward movement of the bars relative to the papers, will cause the needle carrying ends to be thrown up into engagement with the papers.

The paper retracting dogs 87 occupy recesses 73 in the sides of the feed bars 7, being pivoted at 76 and having needles 77 mounted in their rear ends in like manner to needles 81. These dogs carry cam rollers 75 which are adapted to engage the under surface of the projecting edge 65 of plates 63 to thereby depress the needle carrying ends of the dogs to hold their needles 77 out of engagement with the papers. This projecting edge 65 is cut away at 64 and is lacking at the rear end of the feed bar. Springs 78 under dogs 87 will throw their needles 77 up into engagement with the paper when unrestrained by the edges 65. This occurs only during the latter part of their backward movement.

Under the rear of the pile of papers is a supporting bar 9 which has slots 90 therein registering with the feed bars 7, this being done merely to provide convenient means for insertion and removal of the feed bars. A considerable gap is left between bar 9 and the rear ends of the plates 63. The effective width of this is adjusted by the use of a bar 91 which is adjustably mounted on arms 92 which slide in holes in bar 9 and are secured in adjusted position by clamping bolts 93.

A rocker bar 94 extends across the machine beneath and adjacent the rear edge of the pile of papers. This is journaled on ears 98 which are mounted for adjustment on the frame, and are secured when ad-

justed by bolts. The purpose of this is to adjust the jogging arms 95 carried by this rocker bar, for action on papers of somewhat different size, as well as to get the most favorable adjustment for a given size paper.

A link 96 is pivoted to the jogging bar 95 and has a forked or yoke shaped end 97 spanning and guided by shaft 5, or any other suitable guiding support. This link has a cam tappet, or roller 99, which is actuated by engagement with a cam surface 100 upon a member as a disk 101, secured to and rocking with shaft 5. The return movement of the jogging arm is secured by a torsion spring 102 mounted on the shaft 94 (see Figs. 6 and 2). The active faces of jogging bars 95 are preferably roughened or toothed, to prevent sliding of the edges of the papers thereon.

The front plate 2 of the paper receiving bin is supported from a shaft or rod 104 carried in elevated position by posts 105. The upper edge of plate 2 has yokes 106 adapted to embrace shaft 104. The plate may be vertically adjusted by bolts 24 which screw into the yokes 106 and are provided with lock-nuts 107. The lower edge of this plate has a bar 26 which projects beyond its edges and has adjusting bolts 25 engaging a frame member to adjust the lateral position thereof. From the lower edge of plate 2 fingers 22 extend into the paper storing bin, these being raised a short distance above the surface 108 over which the papers are discharged. They are also a short distance above the top surface of the reciprocating, needle-carrying feed bars 7, this distance being in a measure made to conform to a certain relationship with the thickness of the paper sections being operated upon.

The paper when discharged from between the fingers 22 and the surface 108, enters between the feed rolls 109 and are projected thereby through the guiding bars 110, which deliver them to other mechanisms. The feed rolls 109 are held in yielding engagement by mounting one for lateral movement and holding it toward the other by springs 111. Their approach together is limited by a threaded bolt 112.

In the operation of my machine the papers P are placed in their receiving bin or chamber with their folded edges against the front plate 2. This edge of the pile is supported, in part at least, by the fingers 22. The oscillation of the jogging arms 95 keeps the papers well up against the plate 2.

The position of the feed bars 7 shown in Fig. 5, is their extreme advanced or projected position, and the paper which has been removed from the pile is supposed to have been taken away by the feed rolls 109. The back-feed dogs 87 are held in inoperative position by their rollers 75 being under the edges of plates 63.

In moving backward, the frictional engagement of the central boss 85 with the under surface of the papers, rocks their needle carrying ends down to where their needles will not scratch the papers, as is seen in Fig. 4. When the roller 75 of the back-feeding dogs is freed from the projecting edge 65 of plate 63 spring 78 throws up its needle carrying end and its needles 77 engage the lowermost paper to move it backward.

This action is timed to occur only a short time before the termination of the backward movement of the feed bar. In consequence of this and of the gap in the floor just forward of the bar 91, the lowermost paper is buckled downward into this gap, as is shown in Fig. 4. The forward edge of the paper is also pulled off the fingers 22.

When the feed bars 7 are advanced, the frictional engagement with dogs 8 rocks their needle carrying ends to cause their needles 81 to engage the paper. The projection of these needles is such as to penetrate well into, if not mostly through, the lowermost paper. This paper will thus be advanced and projected beneath fingers 22 into the feed rolls 109. The needles of the back-feed dogs 87 will be positively released by being depressed through engagement of their rollers 75 with the port 65 of plates 63.

What I claim as my invention is:—

1. An apparatus for controlling the vertical edges of a stack of papers comprising chains movable downwardly in engagement with the edges of the stack, means for giving these chains an intermittent feed movement and detent pawls acting to prevent upward movement of the papers.

2. An apparatus for controlling the vertical edges of a stack of papers comprising a retaining plate having vertically spaced holes, a chain passing through these holes and having the part extending between these holes lying between the papers and said plate, means for giving this chain an intermittent feed movement and detent pawls engaging the edge of the stack.

3. An apparatus for controlling the vertical edges of a stack of papers comprising vertically movable members, means for giving these an intermittent advancing movement and detent pawls acting to prevent rising of the papers.

4. An apparatus for controlling the vertical edges of a stack of papers comprising vertically movable members, means for giving these an intermittent advancing movement and vertically placed bars at the same side of the pile of papers and a series of spring protruded detent members carried by each of said bars and acting to prevent backward movement of the adjacent edges of the papers.

5. In a machine of the character set forth,

a paper jogging mechanism comprising a reciprocable jogging bar adapted to engage the edges of the papers in a pile, an oscillating arm having a cam surface, a link actuatingly connected with the jogging bar, and a cam-engaging member carried by this link and adapted to be engaged by the cam surface of the oscillating arm.

6. In a mechanism of the kind described, 10 a pivoted jogging bar, a reciprocating actuating member having a cam surface, a link connected with the jogging bar and extending adjacent said cam surface, a cam-contact member mounted for lengthwise adjustment upon said link, and means for similarly adjusting the position of the pivot point of the jogging bar.

7. In a mechanism of the kind described, 20 chains engaging the edges of the papers at one side of the pile, intermittently actuated feeding mechanism for said chains, a movable jogging bar engaging the edges of the papers at the opposite side of the pile, an oscillating arm, actuating connection between 25 said arm and the jogging bar, an actuating member connecting the oscillating arm with the chain actuating mechanism, and means for adjusting the effective length of said arm acting upon said actuating connecting 30 member.

8. A paper feeding mechanism comprising paper supporting members, a feed bar mounted to reciprocate beneath the papers, and having feed dogs hinged thereon, and 35 having a side surface adapted to engage the under surface of the papers to rock the dog upon its pivot.

9. A paper feeding mechanism comprising a reciprocating member having separate 40 oppositely acting feed dogs mounted to rock thereon into and out of engaging position and having surfaces concentric with their pivots positioned to engage the papers to rock the dogs by frictional contact with the 45 papers.

10. A paper feeding mechanism comprising a reciprocating bar, pivoted feed dogs carried thereon and having a paper feeding portion and a separate side surface positioned for continuous frictional engagement 50 with the papers to thereby move the paper feeding portion into and out of engagement with the paper by the reversal of the bar.

11. A paper feeding mechanism comprising 55 a reciprocating bar, pivoted feed dogs carried thereon and having a side surface concentric with its pivot axis and adapted to continuously frictionally engage the papers to rock the dog upon reversal of its carrying 60 member.

12. A paper feeding mechanism comprising 65 a bar mounted to reciprocate along the face of the pile of papers, feed dogs pivotally mounted upon said bar and carrying paper engaging points and having controlling

surfaces frictionally engaging the paper to thereby rock the dog by the movement of the bar into engaging and disengaging position, another dog pivotally mounted on the bar to feed the papers in opposite direction, yielding means acting to engage the latter dog with the papers, and means for restraining the action of this dog to the latter portion of its feeding movement.

13. A paper feeding device comprising a 70 bar mounted to reciprocate along the face of a pile of papers, feed dogs pivoted thereon to oscillate to engage and disengage the papers, said dogs being oscillated by frictional engagement of a side surface with 80 a stationary object.

14. A paper feeding device comprising a 75 bar mounted to reciprocate along the face of a pile of papers, feed dogs pivoted thereon to oscillate to engage and disengage the papers, springs acting upon the dogs to throw them into engaging position, said dogs having surfaces separate from their feeding surfaces adapted to frictionally engage a fixed object to be thereby oscillated 85 as the carrying bar is reciprocated.

15. In a mechanism for delivering papers 90 from a magazine, in combination, a bottom support for the papers having a gap extending transversely of the direction of movement of the papers during discharge, means for varying the width of said gap, and means for engaging a paper to first move its forward part backward and then 95 forward.

16. In a mechanism for delivering papers 100 from the bottom of a pile, in combination, an under-support for the papers having a gap extending transversely of the line of discharge of the papers and located well back from the point of discharge, means for adjusting the width of said gap, an under support for the discharging edge of the papers raised to provide a discharge opening beneath it, and means for engaging the undermost paper of the pile forwardly of the gap to release its discharging edge from its under supports and then forward to discharge it.

17. In a mechanism for delivering papers 115 from a magazine, in combination, a bottom support for the papers having a gap extending transversely of the direction of movement of the papers during discharge, a bar extending lengthwise said gap and adjustable across the gap to vary the width of the gap, under-supports for the discharging edge of the papers holding them slightly raised, and means for engaging the lowermost paper between said gap and the discharging edge to first move it back to clear said under-supports and then forward to eject it.

18. In a device of the character described, 120 in combination, a paper holding magazine, 130

a series of down-holding detents at one side of the magazine, paper jogging members at the opposite side of the magazine, and means for removing the lowermost paper of 5 the pile from the side beneath the down-holding detents.

19. In a device of the character described, in combination, a paper holding magazine, a vertically movable feed chain engaging 10 the edges of the papers at one side of the magazine, an oscillating jogging bar engaging the papers at the opposite side of the

magazine, fingers extending under the edges of the papers at the side of the magazine opposite the jogging bar, the bottom of the 15 magazine having a transversely extending gap, and paper feeding means engaging the lowermost paper between the said fingers and the gap to first move this paper back to release it from said fingers and then forward to discharge it beneath said fingers. 20

Signed at Seattle, Washington, this 31st day of May, 1916.
